UNITED STATES PATENT OFFICE.

OLIVER COLBORNE, OF CHICAGO, ILLINOIS.

PIE-MAKING MACHINE.

No. 821,784.

Specification of Letters Patent.

Patented May 29, 1906.

Application filed January 27, 1906. Serial No. 298,262.

To all whom it may concern:

Be it known that I, OLIVER COLBORNE, a citizen of the United States of America, and a resident of Chicago, Cook county, Illinois, 5 have invented certain new and useful Improvements in Pie-Making Machines, of which the following is a specification.

This invention relates to pie-making machines; and its main object is to save time, 10 labor, and expense in the manufacture of pies by avoiding mechanisms which require the stopping of the pies while performing their respective operations.

Other objects of this invention are to provide a pie-making machine in which the pies 15 are carried along by continuously-moving feeding mechanism and in which the operations of filling the pies, moistening the edges of the crusts, and trimming the crusts are all 20 performed automatically while the pies are being so carried; to provide an improved and compact arrangement of the supporting-frame and conveyer mechanism for devices of this class; to provide an improved form 25 of filling apparatus for measuring and delivering uniform quantities of filling material to each successive pie; to provide improved trimming mechanism adapted to have a purely rolling contact with the edges of the 30 pie-tins and trim the crusts on the tins while said tins are continuously moving along the conveyer; to provide improved means for automatically discharging the pies from the conveyer mechanism, and to provide an im- 35 proved form of crust-trimming mechanism which may be readily adjusted to trim the crusts of pies of different diameters.

These objects are accomplished by the device shown in the accompanying drawings, in 40 which—

Figure 1 is a side elevation, partly in section, of a pie-machine constructed according to this invention. Fig. 2 is a horizontal section of the same on the line 2 2 of Fig. 1. Fig. 45 3 is an end elevation of the crust-trimming mechanism as viewed from the right of Fig. 1. Fig. 4 is a section on the line 4 4 of Fig. 1. Fig. 5 is a detail view showing the relation of the moistening device to the edges of the 50 pie-tins. Fig. 6 is a vertical section of one of the carriers.

In the construction shown the supporting frame consists of a horizontally-disposed platform or table 5, carried by a central pedestal 6. This pedestal is provided with horizontally-disposed arms 7 and 8, extending to-

ward each end of the table 5. Vertically-disposed shafts 9 and 10 are journaled in bearings at the outer ends of the arms 7 and 8, respectively. Each of these shafts has 60 rigidly mounted thereon a pair of sprocket-sheaves 11, which carry an endless-belt conveyer formed of two parallel link belts 12, rigidly connected with each other at regular intervals by carriers 13, which are adapted 65 for supporting pie-tins at their upper ends, as will be hereinafter described.

In the device shown in the drawings the shaft 9 is driven by means of worm-gearing at 14. The shaft 10 is driven from the shaft 70 9 through the link belts 12.

Each of the carriers 13 is provided with a bowl-shaped support 15 at its upper end for supporting a pie-tin at its rim. This support is carried by a hollow shaft 16, which is 75 loosely journaled in the carrier 13 and has a friction-roller 17 rigidly secured at its lower end. A rod 18 extends longitudinally through the hollow shaft 16 and is provided with a pad 19 at its upper end adapted to 80 engage the pie-tin and lift it from the support 15 when the rod 18 is raised. Each of the carriers is also provided with a flanged roller 20. These rollers are adapted to engage the tracks 21 and support the conveyer-belt 85 against sagging at points between the shafts.

A sector 22, having a V-shaped groove in its periphery arranged to fit and have friction contact with the rollers 17, is rigidly secured to the supporting-frame concentrically of the 90 shaft 9. This sector and the rollers 17 cause the pie-tins to be rotated on their own axes while passing around the adjacent portion of the path of the conveyer. A straight bar or toothless rack 23, having a grooved edge corresponding to the periphery of the sector 22, is rigidly secured upon the arm 7 and is adapted to engage the friction-rollers 17 and cause the pie-tins to be again rotated while 100 in position for contact with the crust-trimming mechanism, which will be hereinafter described.

In the drawings the pie-tins are represented at 24. The supports for the pie-tins are preferably arranged so as to support the 105 tins in substantially the same level as the top of the table 5.

The crust-trimming mechanism is mounted in a frame 25, which is mounted upon the table 5 near the shaft 10. A pair of depending swinging frames 26 are hung from a horizontally-disposed shaft 27, which is jour-

naled in bearings in the frame 25. Each of the frames 26 carries a pair of flanged pulleys 28, and these pulleys support the belts 29 and 30, which extend along the conveyer 5 at each side of the path of the pie-tins and are adapted to bear in an inclined position upon the edges of the pie-tins, as shown in Figs. 3 and 4. The frames 26 are normally urged toward each other by the spring 31 and 10 are limited in such movement by an adjustable stop 32, which is adjustably connected to one of the arms 26 and is adapted to engage a lug 33 on the other. This arrangement permits the trimming-belts 29 and 30 15 to yield when in contact with the pie-tins, but normally urges them toward each other, so as to give the desired pressure for cutting off the surplus crust. The belt 29 is driven by the pinion 34, which is driven by a bevel-gear 35, carried by the shaft 27. The belt 30 is driven by a pinion 36, which meshes with a bevel-gear 37 at the other end of the shaft 27. The bevel-gear 35 is driven by a pinion 38 on a vertical shaft 39, which is connected 20 with the shaft 10 by means of the belt and cone-pulleys. (Indicated at 40.) The belts 29 and 30 are driven at somewhat different speeds to conform with the respective resultant speeds of those points on the edges 25 of the pie-tins which are in contact with said belts. It will be seen that, since the pie-tin is rotated through the contact of the friction-roller 17 and the rack 23, the point of the edge of the pie-tin which is adjacent to the 30 belt 30 will be moving along at a considerably less speed than that of the point which has engagement with the outer belt 29, these speeds being resultants of the rotary motion of the pie-tins and their movement along the 35 40 conveyer.

In order to adjust the machine for trimming the crusts of pies of different diameter, the belt 40 is shifted to the corresponding cones of the cone-pulleys, the stop 32 is adjusted to suit the new diameter of the pie-tin, and the gear and pinions 36 and 37 are replaced by others of suitable proportion to drive the belt 30 at the proper speed with respect to the belt 29.

45 The pie-filling material is carried in a cylindrical receptacle 41, which is removably mounted upon the upper end of the shaft 9 and rotates therewith. The receptacle 41 is provided with four discharge-spouts 42, 50 which correspond in spacing to the spacing of the carriers of the conveyer. Each of the spouts 42 is provided with two sliding valves 43 and 44, which are spaced apart sufficiently to measure the proper quantity of filling material for each pie. These valves are 55 respectively operated by cams 45 and 46, which are rigidly mounted on the frame, and are arranged to operate the valves 43 and 44, so that the measuring compartment of each 60 spout between said valves will fill with ma-

terial during a certain portion of each revolution of the shaft 9 and will discharge its contents into the pie-tin during another part of the revolution.

The receptacle 41 is so placed upon the 70 shaft 9 that the pie-tins will each register with one of the spouts 42 while passing around the shaft 9. While the spouts 42 are discharging their contents into the pie-tins, the pie-tins are at the same time rotated 75 through contact of the friction-roller 17 with the sector 22. This rotation serves to cause the filling material to spread evenly over the tin.

A water-tank 47 is mounted on top of the 80 receptacle 41 and is connected, by means of the two pipes 48, with spraying-nozzles 49, one of which is located at each spout 42 in position to moisten the edge of the pie-crust while the pie-tin is passing along a portion of 85 its path around the shaft 9. Each of the nozzles 49 is controlled by means of a spring-valve which is normally closed, but which is arranged to open through the engagement of 90 its stem with a track 51, which is connected with the frame and extends around the desired portion of the path of the pie-tins. The rotation of the pie-tins while the nozzle is discharging a spray thereon insures an 95 even distribution of moisture around the rim of the crust.

A track 52 is mounted on the frame at the extreme left of the machine and extends along the path of the conveyer, being inclined upwardly so as to engage the rods 18 100 of the carriers and wedge said rods upward, raising the pie-tin, as shown in Fig. 1. The pie-tins then pass into the mouth of an inclined delivery-chute 53. As soon as the carrier arrives at the end of the track 52 the 105 rod 18 falls to its normal position, leaving the pie-tin supported by the chute 53. The inclination of this chute permits the pies to be discharged from the machine automatically.

The operation of the device shown is as follows: While the machine is in operation, the conveyer is continuously driven. A pie-tin is placed upon each carrier either automatically or by hand while the carrier is passing along the side of the machine which is at the 115 top of Fig. 2. The lower crusts are then placed upon the tins and the operation of filling the pie takes place while the tin is passing around the portion of the path which is at the right to the shaft 9 in Fig. 2. While the carrier is passing from the filling mechanism to the crust-trimming mechanism, the upper crust is placed upon the pie. The pie then comes into contact with the belts 29 and 30, which bear upon the edges of the tin at an 120 angle thereto and cut off the surplus fringes of crust. While the tins are in contact with the belts 29 and 30, said tins are rotated through the action of the friction-rollers 17 and the friction-rack 23. The belt 29 travels 125 130

at the same rate of speed as the part of the periphery which is adjacent thereto, and similarly the belt 30 travels at a speed corresponding to that of the part of the periphery of the tin which is in contact therewith. The contact between the belts 29 and 30 and the edges of the pie-tins is purely rolling contact, since the speeds of the adjacent points of the peripheries are exactly equal.

10 When the carrier reaches the part of its path which is at the extreme left of Fig. 2, the rod 18 rises upon the track 52, and the pie-tin is lifted and deposited upon the chute 53, as has already been described.

15 What I claim as my invention, and desire to secure by Letters Patent, is—

1. In a pie-machine, the combination of a frame, a crust-trimming device mounted in said frame, and a conveyer adapted to carry

20 a pie-tin and deliver the same to said trimming device, said trimming device being adapted to engage the edge of the tin for trimming a pie-crust thereon while said conveyer is in motion.

25 2. In a pie-machine, the combination of a frame, a horizontally-disposed conveyer for carrying pie-tins along said frame, a crust-trimming device mounted on said frame near the path of said conveyer and adapted to en-

30 gage the edges of the pie-tins for trimming a pie-crust thereon while said conveyer is in motion.

35 3. In a pie-machine, the combination of a frame, an endless-belt conveyer for carrying pie-tins in succession along said frame and adapted to be continuously driven, a crust-trimming device mounted on said frame near the path of said conveyer and adapted to engage the edges of the pie-tins for trimming a

40 crust thereon while said conveyer is in motion.

45 4. In a pie-machine, the combination of a frame, feeding mechanism for carrying the pie-tins singly and in succession along said frame, crust-trimming mechanism mounted in said frame and adapted to engage the edges of the pie-tins carried by said feeding

50 mechanism for trimming pie-crusts thereon while the tins are being carried along by said conveyer.

55 5. In a pie-machine, the combination of a frame and horizontally-disposed conveyer in said frame and adapted to be continuously driven, individual carriers for pie-tins on said conveyer, trimming mechanism disposed above said conveyer and adapted to engage the edges of the pie-tins for trimming pie-crusts thereon while said conveyer is in motion, and means for rotating the tins about

60 their own axes while in contact with said trimming mechanism.

65 6. In a pie-machine, the combination of a frame, a horizontally-disposed conveyer in said frame and adapted to be continuously

driven, individual carriers for pie-tins on said 65 conveyer, trimming mechanism disposed above said conveyer and adapted to engage the edges of the pie-tins for trimming pie-crusts thereon, and means for rotating the tins about their own axes while in contact 70 with said trimming mechanism.

7. The combination of a pie-crust-trimming device, feeding mechanism for conveying pie-tins in succession to said trimming device, means for rotating the pie-tins when in 75 contact with said trimming device, said trimming device having movable trimming members adapted to engage the edges of a pie-tin for trimming a crust thereon and being driven to have rolling contact with said 80 pie-tins, and means for adjusting said trimming members to suit a plurality of different sizes of pie-tins.

8. In a pie-machine, the combination of a horizontally-disposed conveyer adapted to 85 carry a series of pie-tins, a trimming-belt located along the path of said conveyer and adapted to engage the edges of the pie-tins for trimming pie-crusts thereon, mechanism for rotating the tins while in contact with 90 said belt, and means for preventing said tins from tilting on said conveyer through the pressure of said belt.

9. In a pie-machine, the combination of a continuously-moving conveyer for pie-tins, 95 an inclined trimming-surface disposed along the path of said conveyer and adapted to bear upon the edges of the tins carried by said conveyer, means for rotating the tins while in contact with said surface, to insure 100 rolling contact between said surface and the edges of the tins.

10. In a pie-machine, the combination of a continuously-moving conveyer for pie-tins, an inclined trimming-surface disposed along 105 the path of said conveyer and adapted to bear upon the edges of the tins carried by said conveyer for trimming pie-crusts thereon, means for rotating the tins while in contact with said surface to insure rolling contact 110 between said surface and the edges of the tins, a second trimming-surface disposed along said conveyer on the side opposite said first surface, said second surface being driven to travel at the same peripheral speed as the 115 tins.

11. In a pie-machine, the combination of a continuously-moving conveyer for pie-tins, an inclined trimming-surface disposed along 120 the path of said conveyer and adapted to bear upon the edges of the tins carried by said conveyer for trimming pie-crusts thereon, means for rotating the tins while in contact with said surface to insure rolling contact between said surface and the edges of the 125 tins, and a second trimming-surface disposed along said conveyer on the side opposite said first surface, said second surface being driven

- to travel at the same peripheral speed as the tins, said surfaces being normally urged toward each other. 65
12. In a pie-machine, the combination of a horizontally-disposed conveyer adapted to carry a pie-tin, along a pair of endless belts disposed along a portion of the path of said conveyer, being located at opposite sides thereof, and adapted to simultaneously engage the edges of the pie-tin, means other than said belts for rotating the pie-tin while in contact with the belts, and mechanism for driving said belts at speeds respectively equal to those of the tin at its points of contact with the belts. 70
13. In a pie-machine, the combination of a horizontally-disposed conveyer adapted to carry a pie-tin along, a pair of endless belts disposed along a portion of the path of said conveyer, being located at opposite sides thereof, and adapted to simultaneously engage the edges of the pie-tin, means other than said belts for rotating the pie-tin while in contact with the belts, mechanism for driving said belts at speeds respectively equal to those of the tin at its points of contact with the belts, said belts being normally urged toward each other, and an adjustable stop for limiting the movement of said belts. 75
14. In a pie-machine, the combination of a horizontally-disposed conveyer having thereon a plurality of carriers for pie-tins, a delivery-chute extending across the path of said conveyer at a point above the normal position of the tins on the carriers, and mechanism for lifting the tins from said carriers and delivering the same to said chute, substantially as described. 80
15. In a pie-machine, the combination of a horizontally-disposed conveyer, a carrier on said conveyer adapted to support a pie-tin, a vertically-disposed rod mounted in said carrier below the tin and being vertically slideable therein, a delivery-chute extending across the path of the conveyer above the normal position of the tin on the carrier, and a track near said delivery-chute adapted to engage said rod and lift the same for raising the pie-tin to cause the same to be deposited into the chute by the movement of the conveyer. 85
16. In a pie-machine, the combination of a horizontally-disposed conveyer, a carrier on said conveyer adapted to support a pie-tin, a vertically-disposed rod mounted in said carrier below the tins and being vertically slideable therein, a delivery-chute extending across the path of the conveyer above the normal position of the tin on the carrier, a track near said delivery-chute adapted to engage said rod and lift the same for raising the pie-tin above the level of said chute, said rod being normally urged toward its lowered position and said track being adapted to release said rod when the pie-tin is in position to be supported by said delivery-chute. 90
17. In a pie-machine, the combination of a horizontally-disposed conveyer for pie-tins, filling apparatus mounted above said conveyer and adapted to discharge pie-filling material into the tins while said tins and conveyer are in motion. 95
18. In a pie-machine, the combination of a horizontally-disposed conveyer for pie-tins, filling apparatus mounted above said conveyer and adapted to discharge pie-filling material into the tins while said tins are being carried along by said conveyer, and means for rotating the tins on their own axes while receiving material from said filling mechanism. 100
19. In a pie-machine, the combination of a horizontally-disposed conveyer for carrying pie-tins in a horizontal position, a rotating pie-filling device mounted above the conveyer, the path of said conveyer conforming at one part to the path of said filling device, said conveyer and filling device being driven to travel at equal speeds and said filling device being adapted to deliver a measured quantity of filling material to a tin while said tin is being carried along by the conveyer. 105
20. In a pie-machine, the combination of an endless-belt conveyer, sheaves journaled on vertically-disposed axes and carrying said conveyer, a plurality of carriers on said conveyer each adapted to support a pie-tin in a substantially horizontal position, a rotating filling device mounted above one of said sheaves and in axial alinement therewith, said filling device being adapted to travel with a pie-tin while the same is passing around said sheave and to discharge a measured quantity of filling material into the tin while the tin is being carried along by the conveyer. 110
21. In a pie-machine, the combination of an endless-belt conveyer, sheaves journaled on vertically-disposed axes and carrying said conveyer, a plurality of carriers on said conveyer, each adapted to support a pie-tin in a substantially horizontal position, a receptacle for pie-filling material above one of said sheaves and rotatable therewith, and means for discharging a measured quantity of filling material from said receptacle into each tin while said tin is passing around said sheave. 115
22. In a pie-machine, the combination of an endless-belt conveyer, sheaves journaled on vertically-disposed axes and carrying said conveyer, a plurality of carriers on said conveyer, each adapted to support a pie-tin in a substantially horizontal position, a receptacle for pie-filling material mounted above one of said sheaves and rotatable therewith, a spout extending from said tank toward the path of the tins on said conveyer, a measuring device in said spout controlling the discharge thereon and mechanism for operating 120
- 125

- said measuring device for discharging a pre-determined quantity of filling material into each tin while such tin is opposed to said spout.
5. 23. In a pie-machine, the combination of an endless-belt conveyer, sheaves journaled on vertically-disposed axes and carrying said conveyer, a plurality of carriers on said conveyer, each adapted to support a pie-tin in a substantially horizontal position, a receptacle for pie-filling material mounted above one of said sheaves and rotatable therewith, a spout for conducting material from said tank toward the position occupied by a pie-tin in passing around said sheave, a pair of slides extending across said spout and spaced apart, and mechanism for operating said slides to control the flow of filling material through said spout and discharge a measured quantity thereof into each tin while opposed to said spout.
24. In a pie-machine, the combination of a horizontally-disposed conveyer, sheaves on vertically-disposed axes, a receptacle mounted above one of said sheaves and rotatable therewith, a series of carriers on said conveyer, each adapted to support a pie-tin in a horizontally-disposed position, a plurality of spouts extending downward from said receptacle and spaced apart to correspond with the spacing of the carriers, measuring devices in said spouts, and mechanism controlling the discharge of said spouts whereby material will be delivered to the pie-tins while said tins are being carried around the sheave.
25. In a pie-machine, the combination of a horizontally-disposed conveyer, sheaves on vertically-disposed axes, a receptacle mounted above one of said sheaves and rotatable therewith, a series of carriers on said conveyer each adapted to support a pie-tin in a horizontally-disposed position, a plurality of depending spouts extending downward from said receptacle and spaced apart to correspond with the spacing of the carriers, measuring devices in said spouts, mechanism controlling the discharge of said spouts whereby material will be delivered to the pie-tins while said tins are being carried around the sheave, a spraying-nozzle adjacent to each of said spouts and in position for wetting the pie-crust near the rim of the tin, and means for discharging a spray of water upon the crust while the conveyer is in motion.
26. In a pie-machine, the combination of a support for pie-tins adapted to carry the same singly and in succession along a circular path, filling apparatus adapted to move along said path with the pie-tin and to discharge a measured quantity of filling material into the tin while said tin is in motion, and mechanism for rotating the tin while opposed to said filling mechanism.
27. In a pie-machine, the combination of a support adapted to hold a pie-tin in a horizontally-disposed position, a spraying-nozzle adapted to discharge a spray of water upon the edge of the tins, and mechanism for rotating said tin while said spray is in operation.
28. In a pie-machine, the combination of a movable carrier adapted to support a pie-tin in a substantially horizontal position and carry the same along a horizontally-disposed path, a spraying-nozzle mounted above said carrier adjacent to the edge of the tin, said nozzle being adapted to move along said path with the carrier, and mechanism for rotating the tin about its own axis while said nozzle is discharging a spray upon said tin.
29. In a pie-machine, the combination of a movable carrier adapted to support a pie-tin in a substantially horizontal position and carry the same along a horizontally-disposed path, a spraying-nozzle mounted above said carrier adjacent to the edge of the tin, said nozzle being adapted to move along said path with the carrier, and mechanism for rotating the tin about its own axis while said nozzle is discharging a spray thereon, a valve controlling said nozzle and means for automatically opening and closing said valve for discharging a predetermined quantity of water upon the pie-tin.
30. In a pie-machine, the combination of a conveyer adapted to carry pie-tins singly and in succession along a horizontal path, filling mechanism arranged to operate automatically for discharging a measured quantity of filling material into each tin, crust-trimming mechanism adapted to have rolling contact with the edges of the tins for trimming pie-crusts thereon, all arranged to operate while said conveyer is moving continuously.
31. In a pie-machine, the combination of a conveyer adapted to carry a plurality of pie-tins singly and in succession around a horizontally-disposed path, a rotating filling device located at one part of the path of said conveyer, a crust-trimming device located at another point along said path, each of said devices having parts moving with the conveyer and adapted to perform their respective operations while the pie-tins and conveyer are moving continuously.
32. In a pie-machine, the combination of a central pedestal having a pair of horizontally-disposed arms extending in opposite directions; a vertical shaft journaled near the outer end of each of said arms; horizontally-disposed sheaves carried by said shafts; an endless - belt conveyer mounted on said sheaves and having thereon a plurality of carriers each adapted to support a pie-tin in a substantially horizontal position; a receptacle for pie-filling material mounted on one of said sheaves above the conveyer, being rotatable therewith and having a spout extending to a position close to the conveyer and adapted to discharge a quantity of filling ma-

terial into the pie-tin while the same is being carried along by the conveyer.

33. In a pie-machine, the combination of a central pedestal having a pair of horizontally-disposed arms extending in opposite directions; a vertical shaft journaled near the outer end of each of said arms; horizontally-disposed sheaves carried by said shafts; an endless - belt conveyer mounted on said sheaves and having thereon a plurality of carriers each adapted to support a pie-tin in a substantially horizontal position; a receptacle for pie-filling material mounted on one of said shafts above the conveyer, being rotatable therewith and having a spout extending to a position close to the conveyer and adapted to discharge a quantity of filling material into the pie-tin while the same is being carried along by the conveyer; and a crust-trimming mechanism mounted above the

conveyer near the other shaft and adapted to engage the edges of the tins for trimming the crusts thereon, said trimming mechanism being driven by said other shaft.

34. In a pie-machine, the combination of a central pedestal having a pair of horizontally-disposed arms extending in opposite directions, a vertical shaft journaled near the outer end of each of said arms, horizontally-disposed sheaves carried by said shafts, an endless - belt conveyer mounted on said sheaves and having thereon a plurality of carriers each adapted to support a pie-tin in a substantially horizontal position.

Signed at Chicago this 17th day of January, 1906.
